CLOSURE MEANS FOR TUBES

James E. McNeal, Towanda, Pa.

Application February 24, 1942, Serial No. 432,125

1 Claim. (Cl. 221—60)

My invention relates to new and useful improvements in closure means for tubes.

An important object of my invention is the provision of a closure assembly for tubes which may be easily applied to a tube of conventional shape and construction and which will be efficacious in its action to prevent the closure cap of the tube from being lost or misplaced.

Another object of my invention is the provision of a device of the above mentioned character which will permit the closure cap to be readily applied to close the tube or to open the tube.

Still another object of my invention is the provision of a device of the above mentioned character which is efficient in operation, inexpensive to manufacture and simple in construction.

Other objects and advantages of my invention will be apparent during the course of the following description.

In the drawing, forming a part of this specification, and wherein like numerals are employed to designate like parts throughout the same,

Figure 1 is a side elevation of a device embodying my invention and showing the same operatively associated with a conventional tube and closure cap.

Figure 2 is a view similar to Figure 1 but showing the closure cap in the closed position, parts being shown in section and parts in elevation for clearness of illustration.

Figure 3 is a perspective view of the hinge plate and connecting element embodying a part of my invention, and

Figure 4 is a longitudinal sectional view of the nozzle embodying a part of my invention.

In the accompanying drawing, wherein for the purpose of illustration is shown a preferred embodiment of my invention, the numeral 10 designates a collapsible tube of conventional design and construction. The discharge end of the tube is formed with a tapered shoulder 11 which terminates in a threaded neck 12 which conventionally receives the closure cap 13. The closure cap is of conventional construction. The annular skirt portion 14 defines an internally screw threaded socket which conventionally receives the externally screw threaded neck 12 of the tube and the end 15 of the skirt is provided with a radial flange 16 the periphery of which is formed with angularly related facets which enable the user to better obtain a grip thereon for threading and unthreading the same from the tube.

It frequently happens that the cap 13 is lost or misplaced when the contents of the collapsible tube are being used. When the closure cap is lost the contents of the tube dry very rapidly and if not used immediately frequently become entirely dried and must therefore be discarded.

It is my thought to provide a simple and efficient means for holding the closure cap associated with the tube at all times. My device comprises a supporting hinge plate 17 having an opening 18 for receiving the exteriorly screw threaded neck 12 of the tube and a lateral extension 19 which projects substantially laterally of the neck and terminates in a rolled portion 20 which forms a hinge joint for pivotally receiving the supporting wire 21. A nozzle 22 is also attached to the tube. The nozzle is formed with an internal bore 23 which registers with the discharge opening of the neck 12, the lower end 24 of the bore being enlarged and internally screw threaded to receive the neck 12. The nozzle is threaded on to the neck until the lower end 25 thereof seats against the top surface of the plate 17 to securely hold the plate pressed against the shoulder 11 of the tube. The plate is thus held against radial or longitudinal movement relative to the neck by the nozzle and the nozzle is formed at its upper end with an externally screw threaded extension 26 of the same size as the neck 12 of the tube, which extension is adapted to threadedly receive the closure cap 13.

The connecting element 21 comprises a length of wire formed at its middle into a U-shaped portion 27. The base 28 of the U-shaped portion extended through the hinge joint 20 of the plate 17 and the arm portions 29 and 30 thereof extend in laterally spaced relation away from the hinge joint 20. The arm portions 29 and 30 of the connecting element terminate in laterally extending loops 31 and 32 which are provided at the distal ends thereof with eyelets 33 which loosely and slidably receive a respective one of the arm portions 29 and 30. The arm portions of the connecting elements are spaced apart a distance substantially equal to the external diameter of the skirt portion 14 of the closure cap. The skirt portion of the cap is inserted between the loop portions 31 and 32 of the connecting element and the radial flange 15 thereof is received by the loops. The connecting element is preferably formed of an inherently springy wire which may be flexed without being permanently bent. The radial flange of the closure cap is loosely received by the loop portions 55 of the connecting element so that it will be freely

movable therein and the eyelets 33 thereof are movable along the arms 29 and 30 to permit the proper adjustment to be realized. The manner in which the radial flange of the closure cap projects through the flanges will permit the same to be easily grasped between the thumb and finger of one hand whereby to effect rotation thereof onto and from the threaded extension 26 of the nozzle.

It may thus be seen that in operation the plate 17 carrying the connecting element 21 is first applied to the threaded neck 12 of the tube. The nozzle 22 is next applied thereto and threaded thereon into seating engagement with the plate. The closure cap 15 of the tube is next applied to the connecting element in the manner illustrated in Figures 1 and 2. The closure cap may then be easily threaded onto and from the extension 26 of the nozzle and when it is removed therefrom the connecting element 21 will swing in a direction away therefrom as illustrated in Figure 1 to unobstructively position the closure cap while the contents of the tube are being discharged through the bore 23 of the nozzle.

It is to be understood that the form of my invention herewith shown and described is to be taken as a preferred example of the same and that various changes in the size, shape and arrangement of parts may be resorted to without departing from the spirit of my invention or the scope of the appended claim.

Having thus described my invention, I claim:

A cap holder for tubes, comprising a plate 10 adapted to be secured to the neck of a tube, the said plate extending laterally and having its outer end looped to form a hinged joint, and a connecting element formed of a single piece of wire having a central looped portion pivoted 15 within the hinged joint and extending vertically in parallel relation, the upper end of each vertical portion formed with a horizontal looped portion provided with an eye through which the vertical portions pass, whereby the flange of a 20 closure cap is tightly held between the looped portions.

JAMES E. McNEAL.
